FIG. 1 illustrates a top front perspective view of an embodiment of a shipper assembly for a tissue transport system employing an ornamental design in accordance with the present invention;

FIG. 2 illustrates a top rear perspective view of the shipper assembly of FIG. 1;

FIG. 3 illustrates a front view of the shipper assembly of FIG. 1;

FIG. 4 illustrates a rear view of the shipper assembly of FIG. 1;

FIG. 5 illustrates a first side view of the shipper assembly of FIG. 1;

FIG. 6 illustrates a second side view of the shipper assembly of FIG. 1, wherein the second side view is opposite of the first side view;

FIG. 7 illustrates a top view of the shipper assembly of FIG. 1;

FIG. 8 illustrates a bottom view of the shipper assembly of FIG. 1;

FIG. 9 illustrates a cross-sectional view of the shipper assembly taken along the line 9-9 of FIG. 3; and,

FIG. 10 illustrates a cross-sectional view of the shipper assembly taken along the line 10-10 of FIG. 5.

The broken lines are included for the purpose of illustrating unclaimed portions of the shipper assembly for a tissue transport system and form no part of the claimed design.
